UNITED STATES PATENT OFFICE.

JONAS NORTHRUP, OF HOPEDALE, MASSACHUSETTS, ASSIGNOR TO HOPEDALE MANUFACTURING COMPANY, OF MILFORD, MASSACHUSETTS, A CORPORATION OF MASSACHUSETTS.

MISTHREADING DEVICE FOR WEFT-REPLENISHING LOOMS.

1,186,933.

Specification of Letters Patent. Patented June 13, 1916.

Application filed January 14, 1916. Serial No. 72,119.

To all whom it may concern:

Be it known that I, JONAS NORTHRUP, a citizen of the United States, residing at Hopedale, in the county of Worcester and State of Massachusetts, have invented certain new and useful Improvements in Misthreading Devices for Weft-Replenishing Looms; and I do hereby declare the following to be a full, clear, and exact description of the invention, such as will enable others skilled in the art to which it appertains to make and use the same.

The present invention relates to an improvement in misthreading devices for automatic weft replenishing looms.

Automatic weft replenishing looms as ordinarily constructed are provided at one side of the loom with weft replenishing mechanism and on the opposite side of the loom with weft or filling detecting mechanism. When the filling in the active shuttle becomes exhausted or broken, absence of filling is indicated by the detecting mechanism on the next detecting beat of the lay, and on the following or non-detecting beat of the lay a fresh supply of filling is inserted into the shuttle. Should the filling break during its insertion into the shuttle, there occurs what is technically known as a hopper misthread, and on the first shot of the shuttle away from the weft replenishing mechanism no filling is laid in the shed. Should several hopper mistreads occur in succession they would greatly impair the quality of the cloth woven. Three successive hopper mistreads, however, do not impair the quality of ordinary cloth.

If during the operation of the weft replenishing mechanism the filling thread should fail to enter the shuttle eye there occurs what is technically known as a real misthread, and on the first shot of the shuttle away from the weft replenishing side of the loom an intact filling is laid in the shed, so that on the next detecting beat of the lay filling presence is indicated by the detecting mechanism. On the return shot of the shuttle to the weft replenishing side of the loom the filling breaks, but filling presence having been indicated on the preceding detecting beat the weft replenishing mechanism is not set in operation and the shuttle with its broken thread is picked to

the detecting side of the loom and is again returned to the weft replenishing side of the loom before a fresh supply of filling is inserted into the shuttle. It is obvious, therefore, that the occurrence of a single real misthread impairs the quality of the cloth woven more seriously than the occurrence of a single hopper misthread.

It has been proposed heretofore to provide looms with misthreading devices operating to cause loom stoppage on the occurrence of three successive hopper mistreads and also on the occurrence of a single real misthread, but these devices have been somewhat complicated in construction.

The object of the present invention, therefore, is to produce a misthreading device of improved and simplified construction which will operate with certainty to cause loom stoppage on the occurrence of three successive hopper mistreads, on the occurrence of a single real misthread, and on the occurrence of a real mistread preceded either by a single or by a double hopper mistread.

To the accomplishment of this object and further objects which will hereinafter appear the invention consists in the misthreading device described in the following specification and particularly pointed out in the appended claims.

In the accompanying drawings illustrating the preferred form of the invention; Figure 1 is a plan of a part of the left-hand end of a loom showing the application of the improved misthreading device thereto; Fig. 2 is a side elevation partly in section, of the parts shown in Fig. 1; Fig. 3 is a front elevation of the parts shown in Fig. 2; Figs. 4 and 5 are enlarged detail views of the controller and of the resetter viewed from opposite sides; Fig. 6 illustrates the various positions of the misthreading device caused by three successive hopper mistreads occurring during the operation of the weft replenishing mechanism following filling exhaustion or breakage during normal weaving; Fig. 7 illustrates the operation of the misthreading device on the occurrence of one real mistread; and Fig. 8 illustrates the operation of the misthreading device when neither a real nor a hopper mistread occurs during the insertion of a

fresh supply of filling into the active shuttle following filling exhaustion or breakage during normal weaving.

The loom to which the improved misthreading device is attached and of which the left hand end is shown in the illustrated embodiment of the invention may be of any usual or preferred form. The parts of the loom illustrated comprise a breast beam 10 having a shipper slot 11 provided with a recess 12 in which is received the shipper 13 during the running of the loom. A knock-off lever 14 is pivotally supported upon a bracket 15 secured to the breast beam and engages the shipper 13. The filling or detector fork 16 is pivotally supported upon a detector slide 17 which reciprocates forwardly and backwardly in the slide supporting bracket 18 which is secured to the breast beam. The forward end of the slide 17 is provided with a boss 19 which engages the upper end of the detector arm 20 mounted on a rock shaft 21 which extends across the front side of the loom and is connected at the other end of the loom with the weft replenishing mechanism. The weft hammer 23 reciprocates forwardly and backwardly (once to every two forward beats of the lay) under the tail 24 of the detector fork 16, and when the detector fork is depressed upon filling absence the weft hammer hook 25 which is provided with a barb 26 engages the tail 24 and pushes the slide 17 forward, thereby oscillating the detector arm 20 and the rock shaft 21 to set in operation the weft replenishing mechanism. The detector arm 20 and the rock shaft 21 constitute what is known as the filling supply controlling means. If on a detecting beat there is filling presence the detector fork is tilted and then the forward reciprocation of the weft hammer is not communicated to the slide, and consequently the weft replenishing mechanism is not set in operation. The parts described above constitute the filling detecting mechanism and the filling supply controlling means and these parts, their actuating mechanism and mode of operation, together with other parts of the loom necessary to a disclosure of the present invention are well-known to those skilled in the art.

The improved misthreading device is a contrivance operating to cause loom stoppage upon the occurrence of three successive hopper mistreads, upon the occurrence of a single real mistread alone, and upon the occurrence of a real mistread following either a single or a double hopper mistread. This contrivance comprises a knock-off lever actuator 28, a stop delaying device or controller 29, and a resetting block or resetter 30. The knock-off lever actuator operates when the predetermined number of requisite kinds of mistreads have occurred,

to engage the knock-off lever and force it forward, thereby releasing the shipper from its holding notch to stop the loom. The knock-off lever actuator 28 is mounted on a pivot pin 32 journaled in ears 33 and 34 projecting upwardly from the detector slide 17. The forward end or head 35 of the knock-off lever actuator is heavier than the rear end or tail 36, so that the head of the actuator tends constantly to descend into operative position behind the knock-off lever. The head of the actuator is prevented from assuming its operative position behind the knock-off lever, until the proper times, by the engagement of a controller lug 38 with certain portions of the controller 29.

The stop delaying device or controller 29 operates to prevent the knock-off lever actuator from causing loom stoppage until the predetermined number of each kind of mistread has occurred. The controller is wheel-like in shape and is provided with a laterally projecting stud or axle 39. The controller is mounted on its axle 39 for pivotal and vertical movements in an elongated slot 40 formed in an upright 41 rising from the forward end of the detector slide 17. This slot permits the lifting of the controller by the knock-off lever when the latter passes under the former. The forward side of the stop delaying device or controller is provided with a series of rack teeth, 43, 44 and 45, which are adapted to be engaged, on forward movements of the detector slide, by the knock-off lever to impart a progressive or clockwise movement to the controller. The rearward side of the controller is provided with a series of stop controlling notches, two deep notches 47 and 48, and two relatively shallow notches 49 and 50. When because of certain conditions obtaining during the operation of the loom the controller lug 38 is received in either of the deep notches 47 or 48, the knock-off lever actuator will assume its operative position behind the knock-off lever; but, when because of certain other conditions obtaining during the operation of the loom the lug 38 is received in either of the shallow notches 49 and 50, the knock-off lever actuator is held above and clear of the knock-off lever.

The resetting block or resetter 30 is secured to the end of the axle stud 39 which projects beyond one side of the upright 41, and its function is to reset or restore the controller to its normal position. The resetter is in the form of an arm and extends rearwardly. The rearmost end of this arm is provided with a stop lug 52 which extends inwardly laterally behind the rear side of the upright. The resetter is of such construction and is so balanced that it tends constantly to impart an anti-clockwise or retrograde movement to the stop delaying

device or controller. The retrograde or anti-clockwise movement of the controller is limited by the engagement of the lug 52 with the rear side of the base of the upright 41. The progressive or clockwise movement of the controller is limited by the engagement of a lug 53 extending laterally from the controller with the front side of the upright 41. The engagement of the lug 53 with the front side of the upright 41 prevents the resetting block or resetter from overthrowing, that is, from assuming a position from which it cannot be returned by force of gravity.

15 During normal operation of the loom, the parts of the misthreading device are positioned as shown in Fig. 2, with the controller lug 38 resting in a shallow recess 42 formed in the upper surface of the controller.

16 The operation of the misthreading device on the occurrence of three successive hopper mistreads is illustrated in Fig. 6. It is assumed that during the normal operation of the loom, the filling breaks or becomes exhausted so that, on the next detecting beat filling absence is indicated and the detector fork 16 fails to be tilted. Consequently, the weft hammer hook 25 engages the detector fork tail 24 and pushes forward the slide 17 to oscillate the rock shaft 21 through the engagement of the boss 19 with the upper end of the detector arm 20, to set in operation the weft replenishing mechanism for the insertion of a fresh supply of filling in the shuttle. During the normal operation of the loom, the rack tooth 43 is in lowered position behind the knock-off lever 14, and upon the forward movement of the detector slide 17 the rack tooth 43 engages the knock-off lever, as shown in position 1 of Fig. 6, and causes the controller 29 to turn clockwise until the controller lug 38 is received into the shallow notch 49. The occasion of first filling absence always results in the controller lug 38 being transferred from the recess 42 to the notch 49. Upon the return movement of the detector slide 17, the disengagement of the knock-off lever 14 from the rack tooth 43 permits the controller to descend and the rack tooth 44 to assume a lowered position behind the knock-off lever, as shown in position 2. The controller lug 38, however, remains in the notch 49. It is now assumed that during the operation of the weft replenishing mechanism a hopper mistread occurred, that is to say, the filling thread was broken during the transfer of the new bobbin into the shuttle, so that, on the first shot of the shuttle to the detecting side of the loom, no filling is laid in the shed and on the next detecting beat filling absence is indicated. This filling absence causes a second forward movement of the detector slide and the engagement of the rack tooth 44 with the knock-off lever 14, which results in the turning of the controller until the controller lug 38 is received in the notch 50, as shown in position 3. Upon the return of the detector slide, the disengagement of the knock-off lever from the rack tooth 44 permits the rack tooth 45 to assume a lowered position behind the knock-off lever, as shown in position 4, the controller lug 38 remaining in the notch 50. The forward movement of the detector slide 17 resulting from the hopper mistread, set in operation the weft replenishing mechanism, and it is supposed that during the transfer of the fresh supply of filling into the shuttle, a second hopper mistread occurred, so that, on the next succeeding detecting beat filling absence is indicated by the detector fork and a third forward movement of the detector slide takes place. This third forward movement of the detector slide brings the rack tooth 45 into engagement with the knock-off lever 14 and turns the controller until the controller lug 38 is received in the mouth of the deep notch 48, as shown in position 5. By this time, the head 35 of the knock-off lever actuator 29 has been lowered until it rests on the knock-off lever. On the return of the detector slide, the disengagement of the knock-off lever from the rack tooth 45 and the under side of the head of the actuator, permits the actuator to drop into operative position behind the knock-off lever, as shown in position 6. The reception of the controller lug 38 into the deep notch 48 determines the operative position of the knock-off lever actuator behind the knock-off lever on the occurrence of two successive hopper mistreads. It is now supposed that during the operation of the weft replenishing mechanism caused by the third forward movement of the detector slide resulting from the indication of filling absence on the second hopper mistread, a third hopper mistread occurred; filling absence is therefore indicated on the next detecting beat and the detector slide 17 is moved forward a fourth time. This fourth successive forward movement of the detector slide brings the forward end of the head of the knock-off lever actuator into engagement with the knock-off lever, and the continued forward movement of the actuator forces the knock-off lever forward, as shown in position 6, until the stopper lever 13 is disengaged from the notch 12, and the loom is stopped.

17 The operation of the misthreading device on the occurrence of one real mistread is illustrated in Fig. 7. It is assumed that, during the normal operation of the loom, there is breakage or exhaustion of filling. The indication of filling absence on the next detecting beat results in the forward movement of the detector slide 17 and the actuator 29

ation, by the boss 19, of the filling supply controlling means. The forward movement of the slide 17 positions the parts of the misthreading device as shown in position 1, which corresponds to the position of the parts shown in position 1 of Fig. 6. The return of the detector slide leaves the parts as shown in position 2, which corresponds to position 2 of Fig. 6. It will be observed, then, that whenever during normal operation of the loom there is filling absence, the subsequent forward and return movements of the detector slide leave the parts of the misthreading device as shown in positions 2 of Figs. 6 and 7. It will be further observed that, while the parts of the misthreading device are in normal position, as shown in Fig. 2, the tail 36 of the knock-off lever actuator is out of the path of motion of the weft hammer 23, but that after the first forward and return movements of the detector slide, the lowered position of the head of the actuator causes the actuator tail to be raised into the path of motion of the weft hammer 23. It is now assumed that, during the operation of the weft replenishing mechanism occasioned by the breakage or exhaustion of the filling, a real misthread occurred. On the first shot of the shuttle away from the weft replenishing mechanism, filling was laid in the shed, so that, on the next detecting beat, there is an indication of filling presence. Consequently, the tail 24 of the detector fork 16 is raised out of the path of motion of the weft hammer hook 25, and the detector slide 17 remains quiescent while the weft hammer 23 beats forward and strikes the tail 36 of the knock-off lever actuator and oscillates the actuator on its pivot 32 so that the head of the actuator assumes the position shown in position 2 of Fig. 7. The disengagement of the controller lug 38 from the notch 49 permits the resetter 30 to oscillate the controller 29 anti-clockwise until an ear 55 projecting laterally from the upper part of the controller comes into contact with the forward end of the head of the actuator 28. The return beat of the weft hammer 23 disengages it from the tail 36 of the actuator, thereby permitting the head of the actuator to descend. As the head of the actuator descends, the ear 55 is disengaged from the front face of the head of the actuator thus permitting the controller to move anti-clockwise until the controller lug 38 in descending is received in the deep notch 47 in the controller. The notch 47 is of such depth that, when the lug 38 is received therein, the head of the actuator is in operative position behind the knock-off lever, as shown in position 4. The occurrence of the real misthread during the operation of the weft replenishing mechanism having resulted in the indication

of filling presence on the first detecting beat thereafter, the weft replenishing mechanism did not operate when the shuttle was returned to the weft replenishing side of the loom and, consequently, the shuttle with the broken filling thread was returned to the filling detecting side of the loom. Therefore, on the next detecting beat, filling absence is indicated and the weft hammer hook 25 engages the tail 24 of the detector fork 16 to impart a forward movement to the detector slide 17. The forward movement of the detector slide 17 brings the front face of the knock-off lever actuator into engagement with the knock-off lever, as shown in position 5, and forces it forward, thereby stopping the loom.

From the foregoing description it appears that, when the controller lug 38 is in the notch 49, it indicates that there has been filling absence during the normal operation of the loom; that, when the controller lug is in the notch 50, one hopper misthread has occurred; that, when the controller lug is in the deep notch 48, two hopper mistreads have occurred; and that, when the controller lug is in the deep notch 47, it indicates that a filling presence has succeeded a filling absence. It is now supposed that, after the occurrence of a hopper mistread and the consequent positioning of the parts of the misthreading device as shown in position 4 of Fig. 6, the next operation of the weft replenishing mechanism resulted in a real mistread. The first shot of the shuttle away from the weft replenishing mechanism accordingly indicates filling presence, the consequent quiescence of the detector slide 17, and the engagement of the weft hammer 23 on its forward beat with the tail 36 of the actuator 28. The engagement of the weft hammer 23 with the tail 36 oscillates the actuator 28 upon its pivot 32, which permits the resetter 30 to turn the controller anti-clockwise until the ear 55 comes in contact with the front face of the head of the actuator. The return beat of the weft hammer 23 leaves the parts of the misthreading device as shown in position 4 of Fig. 7. A real mistread having occurred after the second succeeding detecting beat there is filling absence and the detector slide 17 moves forward, forces the head of the actuator against the knock-off lever 14, and stops the loom. When two hopper mistreads have occurred and the controller lug 38 is in the deep notch 48, if the third operation of the weft replenishing mechanism results in a real mistread, the subsequent indication of filling presence on the next succeeding or fourth detecting beat will result in the quiescence of the detector slide 17, the engagement of the weft hammer 23 with the tail 36, and the oscillation of the actuator 28 into the position shown in

position 3 of Fig. 7; and as described, the return of the weft hammer 23 will leave the parts of the misthreading device as shown in position 4 of Fig. 7. The occurrence of the real misthread results in the indication of filling absence on the next succeeding or fifth detecting beat, the forward movement of the detector slide, the engagement of the knock-off lever 14 by the knock-off lever actuator, and the stopping of the loom.

The operation of the misthreading device when the action of the weft replenishing mechanism, following exhaustion or breakage of filling during normal running of the loom, results in a properly threaded shuttle, is illustrated in Fig. 8. The filling absence, and the subsequent forward and return movements of the detector slide 17 result in the change of position of the parts of the misthreading device from the position shown in Fig. 2 to that shown in positions 1 and 2 of Figs. 6, 7, and 8. On the next or second detecting beat, filling presence being indicated, the weft hammer 23 coming into engagement with the tail 36 oscillates the actuator 28 to disengage the controller lug 38 from the notch 49, as shown in position 3, thereby permitting the controller 29 to turn rearwardly or anti-clockwise. The return beat of the weft hammer 23 permits the head of the actuator 28 to descend as shown in position 4 until the controller lug 38 is received in the deep notch 47. On the next succeeding or third detecting beat, filling presence being indicated, the weft hammer 23 again engages the tail 36 and oscillates the actuator 28. As the head of the actuator rises, the disengagement of the lug 38 from the notch 47 permits the controller to be turned rearwardly by the resetter 30 until the shallow recess 42 is in the path of downward movement of the lug 38, as shown in position 5. The disengagement of the weft hammer on its return beat from the tail 36 permits the head of the actuator to descend until the lug 38 is received in the recess 42, as shown in position 6. This is the normal position of the parts of the misthreading device and corresponds to the position of the parts as shown in Fig. 2. The first filling presence occurring after a filling absence which has been caused, either by filling exhaustion during normal weaving, or, by either a single or a double hopper misthread, positions the parts of the misthreading device so that the knock-off lever actuator is in operative position behind the knock-off lever, and the second successive filling presence restores the parts of the misthreading device to normal position.

The present invention contemplates a misthreading device having means for causing loom stoppage, means for delaying or controlling the stopping of the loom, that is to say, for determining under what con-

ditions loom stoppage shall take place, and means for automatically resetting or restoring the controlling means to normal position. The parts of the device are mounted on the detector slide. The means for causing loom stoppage is pivotally mounted independently of the stop delaying means and is constructed to move longitudinally with the detector slide when filling is absent on a detecting beat, and pivotally when filling is present on a detecting beat after filling absence. The means for controlling loom stoppage is mounted for pivotal and vertical movements and is constructed for actuation in one direction by engagement with some stationary part of the loom when filling is absent on a detecting beat, and for actuation in the opposite direction by the resetter when filling is present on one or two detecting beats following filling absence. The controlling means is provided with a series of stop controlling depressions or notches of different depths in which is received a member of the loom stoppage means, according to the conditions of loom operation. The arrangement of these notches and the construction of the controlling means are such that, when two hopper mistreads have occurred, the loom stoppage means is in position to cause loom stoppage; so, also, if after filling absence or after a single hopper or a double hopper mistread filling is present on the next detecting beat, the loom stoppage means is in position to cause loom stoppage. If, in either case filling is absent on the next detecting beat, the loom will be stopped; but if in the first case filling is present on the next two detecting beats, or if in the second case filling be present on the next detecting beat, the misthreading device will be restored to normal position. The means for resetting the controlling means is positively connected therewith and is so constructed that, when, on the occasion of one or two filling presences after filling absence, the loom stoppage means is engaged by the weft hammer and thereby disengaged from the controlling means, the resetter imparts a retrograde or resetting movement to the controlling means. The resetting means is prevented from restoring the controlling means to its normal position on the occurrence of the first filling presence after filling absence, by the engagement of a member of the controlling means with the loom stoppage means.

The broad scope of the invention having been indicated and a specific embodiment thereof having been described, what is claimed as new is:—

1. A loom having, in combination, filling supply controlling means, filling detector mechanism including a detector slide, and a misthreading device comprising, means for causing loom stoppage, means for con-

- trolling the operation of the loom stoppage means, and means for automatically restoring the controlling means to its normal position, all the parts of said misthreading device being mounted on the detector slide.
2. A loom having, in combination, filling supply controlling means, a knock-off lever, filling detector mechanism including a detector slide and a misthreading device
- 10 mounted on the detector slide comprising a knock-off lever actuator for actuating the knock-off lever to stop the loom on the occurrence of three hopper misthread or one real mistread, and a controller for preventing the knock-off lever actuator from actuating the knock-off lever until the predetermined number of requisite kinds of misthreads have occurred.
3. A loom having, in combination, filling supply controlling means, filling detector mechanism including a detector slide, a knock-off lever, and a misthreading device mounted on the detector slide comprising, a knock-off lever actuator and a controller,
- 20 said controller having provision for engagement with the knock-off lever to bring the actuator into position to cause loom stoppage on the third successive forward movement of the detector slide.
4. A loom having, in combination, filling supply controlling means, filling detector mechanism including a detector slide, a knock-off lever, a weft hammer, and a misthreading device comprising, a knock-off
- 30 lever actuator, a controller, and a resetter, said controller having provision for forward movement by engagement with the knock-off lever on the occasion of filling absence on a detecting beat, said actuator having provision for engagement by the weft hammer on filling presence following filling absence to permit the resetter to move the controller in the opposite direction to bring the actuator in position to cause loom stoppage.
5. A loom having, in combination, filling supply controlling means, filling detector mechanism, a knock-off lever, and a misthreading device comprising, a knock-off lever actuator including a controller lug,
- 40 and a controller, said controller having a series of stop controlling notches adapted to be engaged by the controller lug to permit the actuator to be operatively positioned with respect to the knock-off lever on the occasion of either three successive filling absences, or a filling presence following three or less filling absences, and to hold the actuator above the knock-off lever on the occasion of either one or two filling absences.
6. A loom having, in combination, filling supply controlling means, filling detector mechanism, and a misthreading device comprising means for causing loom stoppage, a controller for controlling the loom stoppage means, and a resetter, said controller having
- provision for movement in one direction to bring the loom stoppage means into position to stop the loom on the occasion of three successive filling absences, said resetter having provision for moving the controller in the opposite direction to bring the loom stoppage means into position to stop the loom on the occurrence of filling presence after filling absence.
7. A loom having, in combination, filling supply controlling means, filling detector mechanism, a knock-off lever, a weft hammer, and a misthreading device comprising, a knock-off lever actuator, a controller, and a resetter, said controller having provision for movement in one direction on the occasion of filling absence, and said actuator having provision for engagement by the weft hammer to permit the resetter to move the controller in the opposite direction on the occurrence of filling presence following filling absence.
8. A loom having, in combination, filling supply controlling means, filling detector mechanism including a detector slide, a knock-off lever, and a misthreading device comprising, a knock-off lever actuator pivotally mounted on the slide, a controller mounted on the slide for pivotal and vertical movements, and a resetter articulated to the controller.
9. A loom having, in combination, filling supply controlling means, filling detector mechanism including a detector slide, a knock-off lever, a weft hammer, and a misthreading device comprising, a knock-off lever actuator, a controller, and a resetter, said actuator having provision for longitudinal movement by the detector slide on the occasion of filling absence and for pivotal movement by the weft hammer on the occurrence of filling presence following filling absence.
10. A loom having, in combination, filling supply controlling means, filling detector mechanism including, a detector slide, a knock-off lever, and a misthreading device comprising, a knock-off lever actuator, a controller, and a resetter, the controller having provision for movement in one direction by engagement with the knock-off lever on forward movements of the detector slide upon the occasion of successive filling absences, said resetter having provision for moving the controller in the opposite direction to restore it to normal position on the occurrence of two successive filling presences following filling absence.
11. A loom having, in combination, filling supply controlling means, filling detector mechanism, a knock-off lever, and a misthreading device comprising, a knock-off lever actuator including a controller lug, a controller, and a resetter, said controller

- having a series of rack teeth for engagement with the knock-off lever and a series of stop controlling notches, said notches having provision for engagement by the controller lug to determine the position of the knock-off lever actuator.
12. A loom having, in combination, filling supply controlling means, filling detector mechanism, a knock-off lever, and a mis-threading device comprising, a knock-off lever actuator, a controller, and a resetter, said controller having provision for movement in one direction by engagement with the knock-off lever and having provision for movement in the opposite direction by the resetter.
13. A loom having, in combination, filling supply controlling means, filling detector mechanism, a knock-off lever, and a mis-threading device comprising, a knock-off lever actuator having a controller lug, a controller, and a resetter, said controller being provided with a series of stop controlling notches of different depths in which the controller lug is adapted to be received either to position the actuator for causing loom stoppage or to hold it in inoperative position according to whether the predetermined number of the requisite kinds of misthreadings have occurred.
14. A loom having, in combination, filling supply controlling means, filling detector mechanism including a detector slide, a knock-off lever, a weft hammer, and a mis-threading device mounted on the detector slide comprising, a pivoted knock-off lever actuator, a controller mounted for pivotal and vertical movements, and a resetter positively connected with the controller, said actuator and controller having provision whereby the actuator is brought to one position to cause loom stoppage on the occurrence of three successive forward movements of the detector slide and is brought to another position to cause loom stoppage if on the next detecting beat the detector slide remains quiescent.
15. A loom having, in combination, filling supply controlling means, filling detector mechanism including a detector slide, a knock-off lever, and a mis-threading device comprising, a knock-off lever actuator having a controller lug, a controller, and a resetter, said controller being provided with a series of rack teeth adapted to be engaged by the knock-off lever, and a series of stop delaying notches adapted to be engaged by the controller lug when the rack teeth have been engaged by the knock-off lever.
16. A loom having, in combination, filling supply controlling means, filling detector mechanism, a knock-off lever, and a mis-threading device comprising, a knock-off lever actuator having a controller lug, a controller, and a resetter, said controller being provided with a series of stop delaying notches of different depths adapted to be engaged by the controller lug and to position the actuator for loom stoppage when the controller lug is in the deep notches, and to hold the actuator above operative position when the controller lug is in the shallow notches.
17. A loom having, in combination, filling detector mechanism, filling supply controlling means and a mis-threading device comprising means to stop the loom on the occurrence of the hepper misthread and on the occurrence of one real misthread, said means being constructed and arranged to be positioned to cause loom stoppage on the occurrence of filling presence on a detecting beat following filling absence, and means for restoring the loom stoppage means to normal position if there is filling presence on two successive detecting beats.
18. A loom having, in combination, filling detector mechanism, filling supply controlling means, and a mis-threading device comprising means for causing loom stoppage, said loom stoppage means being constructed and arranged to be positioned to cause loom stoppage whenever there is filling presence on a detector beat following filling absence and means for restoring the loom stoppage means to normal position whenever there is filling presence on two successive detecting beats following filling absence.
19. A loom having, in combination, filling detector mechanism, filling supply controlling means and a mis-threading device constructed and arranged to coöperate with and to be controlled in its operation by the filling detector mechanism to be positioned to cause loom stoppage whenever there is filling presence on a detecting beat following filling absence on the preceding detecting beat.

JONAS NORTHRUP.

It is hereby certified that in Letters Patent No. 1,186,933, granted June 13, 1916, upon the application of Jonas Northrop, of Hopedale, Massachusetts, for an improvement in "Misthreading Devices for Weft-Replenishing Looms," errors appear in the printed specification requiring correction as follows: Page 7, line 77, claim 17, first occurrence, for the article "the" read *three*; same page, line 93, claim 18, for the word "detector" read *detecting*; and that the said Letters Patent should be read with these corrections therein that the same may conform to the record of the case in the Patent Office.

Signed and sealed this 25th day of July, A. D., 1916.

[SEAL.]

F. W. H. CLAY,

Acting Commissioner of Patents.

Cl. 139—85.
